UNITED STATES PATENT OFFICE.

HARLEY D. PENNINGTON, OF PITTSBURGH, PENNSYLVANIA, ASSIGNEE TO UNITED ENGINEERING AND FOUNDRY COMPANY, OF PITTSBURGH, PENNSYLVANIA, A CORPORATION OF PENNSYLVANIA.

GALVANIZING MACHINE.

Application filed March 9, 1923. Serial No. 623,947.

To all whom it may concern:

Be it known that I, HARLEY D. PENNINGTON, a citizen of the United States, residing at Pittsburgh, in the county of Allegheny and State of Pennsylvania, have invented a new and useful Improvement in Galvanizing Machines, of which the following is a full, clear, and exact description.

The present invention relates to the act of coating sheet material, and more particularly to an improved galvanizing machine, the present application being a continuation in part of my copending application Serial No. 530,505, filed January 20, 1922.

In a galvanizing machine, it is necessary, at frequent intervals, to raise the supporting frame in order to lift the parts carried thereby out of the vat for cleaning. It has heretofore been the practice to mount the motor and the driving connections intermediate the motor and gearing on the various rolls on a sliding base adapted to be moved towards and away from the rolls by means of a screw. With this arrangement, whenever it was desired to raise the frame, it was necessary to back off the motor and driving connections by means of the screw. This was not only a laborious operation, but one which required considerable time. Now in a machine of this character, it is desirable to be able to disconnect the driving means from the rolls quickly, in order to enable raising of the frame and separation of the rolls and other parts therefrom for cleaning before the hot coating material has had time to cool and harden on the parts. An important object of the present invention, therefore, is to provide a machine wherein the driving means can be quickly disconnected from the rolls without the necessity for backing off the motor.

It has also heretofore been the practice to mount the intake rolls directly over the flux box. A serious objection to this arrangement is that the flux splashes up on to the peripheral surfaces of the rolls and causes these surfaces to become rough and pitted, so that the metal sheets passing between the rolls are dented and otherwise damaged. Conse-

quently, another object of the invention is to provide an arrangement of flux box and intake rolls wherein this objection is overcome.

It has further been the practice heretofore to drive one of the exit rolls through the other by means of a gear mounted on one end of one of said rolls meshing with the gear on the corresponding end of the other roll, said gears being of substantially the same diameter as the rolls. Now the exit rolls, due to wear and frequent dressings, become gradually smaller and smaller in diameter, and, as their diameters become less, they must be moved relatively towards each other, but where the rolls are directly geared together in this manner, they cannot be moved towards each other, except to a very limited extent, and, hence, it is necessary to change the gears on the rolls at frequent intervals, or to replace the rolls frequently. Either procedure involves great loss of time and large expense. A further object of the present invention is, therefore, to provide an arrangement for driving the exit rolls which permits the rolls to move towards each other without the necessity of changing the gears during the life of the rolls.

It sometimes happens that a sheet passing through the pot sticks in the guides. In such cases, if another sheet is fed in behind this sheet, damage to the machine, as well as to the sheets, is likely to occur. Still another object of the present invention is to provide means whereby a workman can instantaneously disconnect the driving connection between the motor and intake rolls.

A further object of the invention is to provide means whereby the vertical worm shaft and worm which drive the lower of the intermediate or bottom rolls may be swung away from said rolls to facilitate removal of the latter, and whereby the said worm may be quickly removed from said worm shaft.

A preferred embodiment of the invention is illustrated in the accompanying drawings, in which:

Figure 1 is a plan view of the machine,

Figure 2 is a vertical longitudinal sectional view of the machine.

5 Figure 3 is a vertical sectional view taken on the line III—III of Figure 1, and looking in the direction of the arrows,

Figure 4 is a fragmentary view, partly in section and partly in elevation, illustrating the means for driving the intermediate or bottom rolls,

10 Figure 5 is a view taken on the line V—V of Figure 4,

Figure 6 is a vertical sectional view taken on the line VI—VI of Figure 1, and looking in the direction of the arrows,

15 Figure 7 is a sectional view taken on the line VII—VII of Figure 6,

Figure 8 is a view similar to Figure 7 illustrating the manner in which the exit rolls are permitted to approach each other 20 by the gearing arrangement shown,

Figure 9 is a plan view of the driving means and of the driving connections between the driving means and the rolls,

25 Figure 10 is a side elevation corresponding to Figure 9 with the motor removed, and

Figure 11 is a view taken on the line XI—XI of Figure 10.

Referring to the drawings, the reference 30 numeral 2 indicates the masonry foundation upon which the machine is supported, and 3 the pot or vat for holding the coating bath.

Overlying the pot 3 and resting at its 35 ends upon the foundation 2 is a rectangular supporting frame 4 comprising parallel side beams 5 and 6 and transverse hollow tie members 7 and 8. The supporting frame 4 is constructed and arranged to be wholly 40 above the level of the bath in order that the same may not be subjected to the corrosive action of the coating material.

45 Detachably connected to the side members 5 and 6 and depending into the pot 3 are a pair of oppositely arranged U-shaped roll housings 9 and 10 for a pair of intermediate or bottom rolls 11 and 12. These rolls are journaled at their ends in upper and lower bearing blocks 13 and 14 slidably mounted 50 in the roll housings. Resting upon the upper face of each upper bearing block 13 is a separator plate 15. Each of the separator plates is engaged by the lower end of a vertically slidable rod 16 suitably guided in 55 the frame 4 and engaged at its upper end by a weighted lever 17 pivoted to the frame at 18, the weighted levers 17, through the rods 16, separator plates 15 and bearing blocks 13, maintain a suitable pressure between the rolls 11 and 12.

60 Fixed to one end of the lower roll 12 is a worm gear 19, and fixed to the other end of the roll is a gear 20 meshing with a similar gear 21 on the end of the upper roll 11.

65 Journaled in a bushing 22, the latter jour-

naled in a bracket 23 secured to the side beam 5, is a short driven shaft 24 having fixed to its inner end a bevel gear 25 in mesh with a similar bevel gear 26 secured to the upper end of a vertical worm shaft 27. The 70 lower end portion 28 of the shaft 27 is reduced in cross section and slidably mounted thereon to turn therewith is a worm 29 arranged to mesh with worm gear 19. Bolted to the lower end of the housing 9 is a pair 75 of strap members 30, each having a flange 31 at its free end, said flanges being directed towards each other, the opening between them permitting the passage therethrough of a bearing member 32 and the end portion 80 28 of the shaft 27. For maintaining the worm 29 in engagement with the gear 19, a wedge member 33 is inserted between the flanges 31 and the bearing member 32, the wedge being secured to the lower end of a 85 rod 34. The rod 34 has a threaded upper end extending through an opening in the frame 4, and mounted on its threaded upper end are nuts 35, by means of which the rod is moved longitudinally to adjust the position of the wedge 33.

Referring to Figure 4, it will be seen that the lower half of the housing 36 for the gears 25 and 26 and the upper end of the worm shaft 27, is formed integral with the 90 bushing 22. Due to this construction, when the wedge 33 is removed from between the bearing 32 and the flanges 31, and the bearing 32 removed, the shaft 27 can be swung away from the rolls, as indicated in chain 100 lines in Figure 5. When the shaft 27 is in this position, the worm 29 can be removed therefrom for cleaning, merely by striking the same a blow with a hammer, whereupon the worm will slide from the lower end 28 105 of the shaft. Then, to remove the rolls 11 and 12 and their bearings from the housings 9 and 10, all that is necessary is to swing the weighted levers 17 out of engagement with the rods 16, raise or remove the 110 latter, insert a bar under the upper bearings 13 and raise them until they clear the upper roll 11, whereupon they can be pushed inwardly to disengage them from the housings, then remove the upper roll 11 through 115 the window in the housing 10, then lift the lower roll 12 to clear the bearings 14 and remove it through the window in the housing 10, and finally remove the bearings 14 from the housings. Thus it will be seen 120 that I have provided means for driving the intermediate or bottom rolls 11 and 12 which greatly facilitates removal of the rolls and their bearings, and also removal of the worm 29.

125 Supported by the frame 4 and depending into the pot 3 adjacent the forward end of the latter is the usual flux box 37. Now, as has already been pointed out, it is the usual practice to mount the intake rolls over the 130

flux box, but with this arrangement, the molten material in the flux box splashes up on the rolls and causes their surfaces to become rough and pitted, so that the sheets 5 passing between the rolls are damaged. To avoid this difficulty, I mount the intake rolls 38 and 39 at a considerable distance in front of, as well as above, the flux box 37 and provide guiding means 40 between the rolls 10 and box. With this arrangement, danger of the flux splashing up over the rolls is practically eliminated.

At the opposite end of the frame 4 are located the exit rolls 41 and 42 and the large 15 roll 43, the latter being journaled in open bearings 44. Arranged in the pot 3 and supported by the frame 4 are the usual guides 45, and suspended in front of the exit rolls is a plate 46 for protecting these 20 rolls from the dross floating on top of the bath.

The means for driving the exit rolls is 25 illustrated in Figures 6, 7 and 8, and comprises a driven shaft 47 extending through the side beam 5 and journaled in suitable bearings. Fixed to the inner end of the shaft 47 is a gear 48 meshing with a gear 49 journaled in the frame 4, and with a gear 50 on the exit roll 41. The gear 49 meshes 30 with a gear 51 on the exit roll 42. It will be noted, by reference to Figure 6, that the gears 50 and 51 are in different parallel vertical planes, and that the gears 48 and 49 are considerably wider than the gears 35 50 and 51. It will be evident that this arrangement permits the rolls 41 and 42 to move towards each other, as their diameters become less, until the reduced end 52 of the roll 42 comes in contact with the gear 50 40 on the roll 41. The relative positions of the gears when the rolls 41 and 42 are new are illustrated in Figure 7, and their relative positions after the rolls have become reduced in diameter are illustrated in Figure 45 8. For urging the rolls 41 and 42 relatively towards each other, the usual weighted levers 53 are provided, these levers being pivoted intermediate their ends to the frame at 54 and bearing at one end against the 50 bearing portions 55 of roll 42. The advantages of the gearing arrangement described over the usual arrangement in which the exit rolls are geared directly together, will be apparent, as the described arrangement 55 obviates the necessity for changing the gears on the rolls during their useful life.

The means for driving the various sets of rolls is illustrated in Figures 9, 10 and 11, and comprises a motor 56 which drives a 50 worm shaft 57 through suitable change-speed gearings 58 and 59 arranged in the housing 60. The worm shaft 57 carries worms 61, 62 and 63, which engage worm gears 64, 65 and 66 on shafts 67, 68 and 69. 65 The shaft 67 has secured to an end there-

of a sleeve 70 having a bore 71 of non-circular cross section, and secured therein by means of a set screw 72 is the end of a bar 73, also of non-circular cross section. Journaled on the end of the shaft 75 of the intake roll 39 is a clutch member 74 having a bore of non-circular cross section receiving the opposite end of the bar 73. Slidably mounted upon the shaft 75 for rotation therewith and for cooperation with the 75 clutch member 74 is a clutch member 76. Extending through the hollow tie rod 7 is a rod 77 operatively connected at one end to the clutch member 76 and at its other end to an operating lever 78. The shaft 75 is 80 arranged to drive the usual wringer rolls 79 and 80 through the sprocket wheels 81 and 82 on shaft 75 and shaft 83 of roll 80 and the connecting sprocket chain 84.

The described driving connection between 85 the shafts 67 and 75 provides means whereby a workman, standing at the opposite side of the supporting frame 4 from the driving means, can instantly render inoperative the driving connection between the 90 shaft 75 and bar 73, and thereby stop rotation of the intake and wringer rolls. It is of great advantage to be able to do this when a sheet becomes stuck in passing 95 through the machine, as has already been pointed out.

The shaft 68 is operatively connected to the shaft 24 by means of a sleeve 85 and bar 86, these parts corresponding to the parts 70 and 73. One end of the bar 86 is 100 secured in the bore 71 of sleeve 85 by a set screw 72, and the other end engages in a bore of non-circular cross section in the end of the shaft 24, but is not secured therein.

The shaft 69 drives a shaft 87 through 105 speed-change gearing arranged in the housing 88. This speed-change gearing comprises a plurality of gears 89 of different sizes mounted on the shaft 87 and a gear 90 on shaft 69 meshing with a gear 91 journaled in a supporting member 92. The supporting member 92 is bifurcated to straddle the gears 90 and 91 and is journaled at one end upon the shaft 69. At its other end the supporting member 92 carries a spring-actuated pin 93 adapted to engage any one of a plurality of holes 94 in the housing 88 to hold the gear 91 in mesh with the desired one of the gears 89. 110

The shaft 87 has secured thereto a sleeve 120 95 and a bar 96, similar to the bars 73 and 86, operatively connects the sleeve 95 with shaft 47, said bar 96 being secured at one end in the bore 71 of sleeve 95 by a set screw 72, and having its other end projecting into a bore of non-circular cross section in the end of shaft 47, but not secured therein. The shaft 97 of roll 43 is driven through sprockets 98 and 99 on shafts 47 and 97 and sprocket chain 100. 125

The driving means, comprising the motor 56 and shafts 67, 68 and 87, is mounted upon a stationary base spaced from the supporting frame 4. The bars 73, 86 and 96 constitute a readily detachable driving connection 5 between the driving means and the rolls. It will be seen that the bar 73 can be disconnected from the shaft 75 merely by loosening the set screw 72 and moving the bar 73 10 longitudinally away from the supporting frame. In like manner, the bar 86 can be disconnected from the shaft 24 and the bar 96 from the shaft 47. By reason of the fact that the bars 73, 86 and 96 are secured only 15 at their ends remote from the frame 4, these bars can be manipulated at their cooler portions for disconnecting the driving means from the rolls, and this is obviously an advantageous feature. The particular advantage, however, of this construction and arrangement of the driving means and driving connections between the driving means and rolls, arises from the fact that it obviates the necessity for backing the driving 20 means away from the supporting frame in order to disconnect the driving means from the rolls, it only being necessary to move the bars 73, 86 and 96 for this purpose.

I claim:

- 30 1. In a coating machine, a roll, stationary driving means spaced from said roll, and an elongated member operatively connected at one end to said driving means and at its other end to said roll, said member being adapted to be moved longitudinally to disconnect it from said roll, substantially as described.
- 40 2. In a coating machine, a supporting frame, a plurality of rolls journaled therein, stationary driving means spaced from said frame, and an elongated member operatively connecting each of said rolls with said driving means, said members being movable longitudinally to disconnect them from said rolls, substantially as described.

- 50 3. In a coating machine, a plurality of sets of rolls, driving means, means operatively connecting said driving means with each set of rolls, and a clutch in the driving connection between said driving means and one set of rolls whereby to render said driving connection inoperative at will, substantially as described.

- 55 4. In a coating machine, a supporting frame, a roll journaled in said frame, driving means on one side of said frame, a driving connection between said roll and driving means, and means operable from the other side of said frame for rendering said driving connection inoperative, substantially as described.

- 60 5. In a coating machine, a supporting frame, a roll journaled in said frame, stationary driving means spaced from said frame, an elongated member operatively con-

necting said driving means with said roll and adapted to be moved longitudinally away from said frame for disconnecting it from said roll, and releasable means engaging the end of said member connected to said driving means for normally preventing longitudinal movement thereof, substantially as described.

6. In a coating machine, a roll, stationary driving means spaced from said roll and including a shaft, a sleeve mounted on said shaft, a shaft for rotating said roll, a sleeve mounted on said last mentioned shaft, each of said sleeves having a bore of non-circular cross section, and an elongated member of non-circular cross section at its ends having one end engaging in the bore of one of said sleeves and the other end engaging in the bore of the other of said sleeves, said member being movable longitudinally to disengage it from the sleeve carried by the shaft for rotating the roll, substantially as described.

7. In a coating machine, a roll, stationary driving means spaced from said roll, a shaft for operating said roll, an elongated member operatively connected at one end to said shaft and at its other end to said driving means, said member being adapted to be moved longitudinally to disconnect it from said shaft, a clutch in the connection between said member and shaft, and means for operating said clutch, substantially as described.

8. In a coating machine, a supporting frame, a plurality of rolls journaled therein, stationary driving means spaced from said frame, and driving connections between said driving means and rolls bodily movable in the direction of said driving means for disconnecting said driving means from said rolls, substantially as described.

9. In a coating machine, supporting means, a roll journaled therein, stationary driving means spaced from one side of said supporting means, a shaft for rotating said roll, an elongated member operatively connected at one end to said shaft and at its other end to said driving means, said member being adapted to be moved longitudinally to disconnect it from said shaft, a clutch in the connection between said member and shaft, and means operable from the side of said supporting means opposite from said driving means for operating said clutch, substantially as described.

10. In a coating machine, a pair of exit rolls, a gear fixed to one end of one of said rolls, a gear fixed to the corresponding end of the other roll but arranged out of the plane of said first gear, a shaft parallel to the axes of said rolls, a gear fixed to said shaft and meshing with the gear on one of said rolls, a gear meshing with the gear on said shaft and with the gear on the other

roll, and means for driving said shaft, substantially as described.

11. In a coating machine, a pair of exit rolls, a gear fixed to an end of one of said rolls, a gear fixed to the corresponding end of the other of said rolls but arranged out of the plane of the first gear, and means for driving said gears, substantially as described.

12. In a coating machine, a pair of exit rolls, one of said rolls having a reduced end, a gear fixed on said reduced end, the other of said rolls having a reduced end extending beyond the reduced end of the first roll and having a gear fixed thereon but arranged out of the plane of the first gear, and means for driving said gears, substantially as described.

13. In a coating machine, supporting means, a roll journaled therein, a shaft, means for driving said shaft, a driving connection between said shaft and said roll, a bearing for said shaft arranged to permit said shaft to be swung about an axis, and releasable means for normally holding said shaft in position to maintain said driving connection between said shaft and roll, whereby said shaft may be swung about said axis to disconnect said driving connection when released from said holding means, substantially as described.

14. In a coating machine, supporting means, a roll journaled therein, a shaft having a reduced end portion, means for driving said shaft, a gear fixed to an end of said

roll, a gear slidably mounted on said reduced end of said shaft, a bearing for said shaft arranged to permit said shaft to be swung about an axis, and releasable means for normally holding said shaft in position to maintain said gears in mesh and for preventing the gear on said shaft from sliding off said reduced lower end, whereby said shaft may be swung about said axis to move the gear thereon out of engagement with the gear on said roll and to permit said gear on said shaft to slide off of said reduced end, substantially as described.

15. In a coating machine, a supporting frame, a roll journaled therein and having a gear fixed to one end thereof, a shaft having a gear on one end thereof adapted to operatively engage the gear on said roll, a second shaft journaled in said frame and having its axis at right angles to said first shaft, a gear on one end of said second shaft meshing with a gear on the other end of said first shaft, a bearing for said first shaft arranged to permit the same to be swung about said second shaft as an axis, and releasable means for normally holding said first shaft in position to maintain the gear connection between the same and said roll, whereby said first shaft may be swung about said axis to release said gear connection between the same and said roll when released from said holding means, substantially as described.

In testimony whereof I have hereunto set my hand.

HARLEY D. PENNINGTON.
